UNITED STATES PATENT OFFICE.

FRANK W. WATERMAN, OF BALTIMORE, MARYLAND.

APPARATUS FOR EXTRACTING TURPENTINE AND RESINOUS SUBSTANCES FROM WOOD.

1,099,779.

Specification of Letters Patent. Patented June 9, 1914.

Application filed October 5, 1910. Serial No. 585,660.

To all whom it may concern:

Be it known that I, FRANK W. WATERMAN, a citizen of the United States, residing at Baltimore city, State of Maryland, have invented new and useful Improvements in Apparatus for Extracting Turpentine and Resinous Substances from Wood, of which the following is a specification.

My present invention relates to improvements in apparatus for extracting turpentine, resin and other fatty or gummy substances from wood and especially from wood when in a divided condition, such as sawdust or chips, and it has for its object primarily to provide an improved and more efficient apparatus of this class which is capable of rapidly extracting such by-products in good condition and practically free from impurities or injury, and the resulting pulp can be recovered free from turpentine and resin and in an unimpaired condition so that it may be used advantageously in the manufacture of paper and other articles made from pulp, the apparatus being so constructed that the various operations necessary to obtain the foregoing results are taking place simultaneously whereby the greatest efficiency and capacity is obtained with an apparatus of given size.

A further object of the invention is to provide a retort superposed on a digester for use in connection with an apparatus of the class specified, the upper or superposed retort first receiving the wood and operating thereon to extract the turpentine and other volatile substances, and the digester subsequently receiving the residue direct from the retort and operating thereon at a relatively higher temperature to extract the resinous substances, simple but efficient devices being provided for transferring the residue from the retort to the digester and for discharging the final residue from the digester.

To these and other ends, the invention consists in certain improvements, and combinations and arrangements of parts, all as will be hereinafter more fully described, the novel features being pointed out particularly in the claims at the end of the specification.

In the accompanying drawing: Figure 1 shows an apparatus constructed in accordance with my present invention, the parts being shown in elevation and certain elements of the apparatus being shown in sec-

tion; and Fig. 2 is a plan view of the apparatus shown in Fig. 1.

Similar parts are designated by the same reference characters in the several views.

In the present instance, the apparatus embodies two chambers, a retort 1 and a superposed digester 2, these chambers being mounted in superposed relation upon a suitable supporting frame 3 and the upper chamber 1 is mounted directly over the lower chamber 2. The upper chamber has an opening 4 through which the wood may be introduced and this opening may be provided with a suitable closure 5 to prevent the escape of the evolved vapors during the operation of the apparatus. The lower end of this chamber is preferably provided with a conical or hopper-shaped bottom 6, and an outlet or discharge pipe 7 is fitted into the opening in the bottom. It is preferable that the wood within the chamber 1 should not rest directly upon the bottom 6 in order that suitable space may be provided for liquid which accumulates in the bottom of the retort chamber 1. In the present instance, I have provided a foraminous support 8 which rests at its periphery upon the bottom 6, and this support is in the form of a truncated cone having an angle greater than the angle of the bottom 6 so as to form a liquor-receiving space 9 beneath it. A foraminous tube 10 forms a continuation of the support 8 and leads into the discharge pipe 7.

Any suitable means may be provided for heating the mass of material in the chamber 1 to a temperature that will be sufficient to distil or volatilize the turpentine or other volatile substances but will be insufficient to impair their quality. A temperature for example ranging between 200 and 212° F. will be suitable for this purpose. In the present instance, I have shown a spiral coil 11 which is interposed between the bottom 6 of the chamber and the support 8, this coil having an inlet 12 to receive steam at a suitable temperature and an outlet 13 for discharging such steam and the condensate. A pipe 14 enters the upper portion of the chamber 1 and this pipe may be connected to a steam supply pipe 15 and a water supply pipe 16, these pipes 15 and 16 being provided with suitable valves whereby water may be admitted to the chamber 1 to form a solution for the mass of wood therein, and

after the turpentine and volatile substances have been distilled off, steam may be admitted to the chamber from the pipe 15 so as to discharge the residual mass from the chamber 1 and transfer it to the chamber 2. The discharge pipe 7 which forms a fluid pressure-tight connection between the chambers 1 and 2 is provided with a suitable valve 17 which is normally closed during the operation of the apparatus but is opened to permit the transfer above-mentioned to take place.

18 represents a still which is adapted to receive the fluids from the chamber 1, a pipe 19 in the present instance being connected to the still and having one branch 20 which is valved and leads from the liquor-receiving chamber 9 in the bottom of the chamber 1 and having a second branch 21 which communicates with the upper portion of the chamber 1, the pipe 21 being also provided with a suitable valve. The still 18 contains a suitable heating coil 22 the bends of which are preferably arranged in a vertical plane so as to avoid obstructing the passage of the substances within the still when the same are discharged through a discharge valve 23 at the bottom of the still, and a gas or other suitable burner 24 may be mounted beneath the still to supplement the heating effect of the steam coil 22 and thereby raise the temperature within the still to a point sufficiently high to melt any resin that may be carried over with the turpentine or volatile substances from the upper chamber 1. The cock 23^a being closed, vapors from the still are conducted therefrom through a pipe 25 through a valve 25^a into a condensing coil 26, the latter being contained as usual within an appropriate cooling tank 27, and the outlet end of the condensing coil is immersed within a bath of water 28 contained in a collecting tank 29, the latter having a weir 30 over which the turpentine, which will rise to the surface of the water, may overflow. A supplemental valve-controlled pipe 25^b may be provided in the top of the still to permit the escape of water during the evaporation of the latter subsequent to the extraction of the turpentine.

The lower digester chamber 2 receives the residue upon the completion of each distilling operation as carried on in the upper chamber 1, this chamber 2 having a cover 31 which is connected to the discharge pipe 7, and the lower end of the chamber 2 is closed by a bottom 32 which is preferably conical or hopper-shaped and is provided with a discharge valve 33 through which the pulp freed of the turpentine and resin may be discharged. This lower chamber may also be provided with a foraminous support 34 upon which the mass of material may rest forming a collecting space 35 beneath it. The material while in the chamber 2 is

subjected to a temperature higher than that to which the wood in its natural condition is subjected in the chamber 1. A temperature for example of 310° F. may be used in the lower retort chamber 2. Any suitable means may be provided for so heating the mass. In the present instance, I have provided a vertically arranged closed or imperforate heating coil 36 which may lie in close proximity to one wall of the chamber in such a way as not to obstruct the movement of the mass while being discharged through the valve 33, and the heating effect of this coil 36 may be supplemented by an appropriate burner 37 arranged beneath the bottom of the chamber. A discharge pipe 38 leads from the collecting chamber 35 to a suitable collecting vessel 39, this pipe serving to discharge the resinous or gummy substances that are set free from the mass. If so desired, means may also be provided for maintaining a constant circulation within the chamber 2 during the distilling operation, a steam inlet pipe 40 entering the chamber 2 at the top and leading downwardly into the collecting chamber 35 where it is provided with a nozzle 41, this nozzle being located at the mouth 42 of an ejector pipe 43. The residue pulp may be discharged from chamber 2 by steam from pipe 44.

In operation, a mass of the wood in the form of sawdust or chips is introduced into the chamber 1 through the opening 4, and a suitable quantity of water is admitted to the chamber 1 to thoroughly soak the wood through the pipe 16. Steam is then admitted to the coil 11 and the mass in the upper retort is heated and maintained at a suitable temperature below the boiling point of water and for a period sufficient to distill off the turpentine and any other volatile substances. Such vapor as may escape from the top of the solution may reach the still through the upper branch pipe 21, the lower branch pipe 20, however, being kept closed until practically all of the turpentine has been freed from the mass. Upon the completion of the distilling operation in the chamber 1, the pipe 20 may be opened and the liquor contained in this chamber will pass through the pipes 19 and 20 into the still 18 carrying with it the turpentine and other volatile substances. Communication through the pipes 20 and 21 is then cut off, the valve 17 in the discharge pipe 7 is opened, and steam is admitted from the steam pipe 15 into the chamber 1, this steam acting upon the mass of material and causing it to discharge from the chamber 1 through the pipe 7 and into the lower chamber 2, it being understood that the pipe 7 has pressure-tight connections with the chambers 1 and 2, and after this transfer of the mass from one chamber to the other, the

intermediate valve 17 is again closed, the steam from the pipe 15 is cut off, and a new charge of material may be introduced into the chamber 1 through the inlet 4. The material received by the chamber 2 from the chamber 1 has been deprived of its turpentine and other volatile substances, and this mass is further treated in the chamber 2 at a higher temperature, the temperature being sufficiently high to free the mass of resinous or gummy substances which collect in the space 35 at the bottom of the chamber 2, and these gummy or resinous substances find an outlet through the pipe 38 and into a suitable collecting receptacle 39. During the treatment of the mass within the chamber 2, suitable alkaline solution may be introduced therein to dissolve out the resinous substances from the wood while the latter is boiled in this chamber, and this solvent which discharges subsequently into the receptacle 39 with the resinous and gummy substances may then be recovered in any known manner. The second step in the operation takes place in the chamber 2 while the first step in the operation is taking place in the upper chamber 1 and during these two steps in the operation, the turpentine and volatile substances discharged into the still from the upper chamber are being distilled and recovered from the water, the turpentine being evaporated from the watery solution within the still and after passing through the condensing coil 26 passes as a liquid into the water bath 28 and, owing to its specific gravity, the turpentine will rise upon the surface of this separator and will flow over the weir or dam 30. By observing the nature of the substance discharging from the condensing coil, it may be determined immediately when the distillation of the turpentine is at an end, and the valve 25^a in the discharge pipe 25 of the still may then be closed and the temperature within the still increased to a point where it will melt any resinous substances that may have been carried over into the still toward the end of the treatment in chamber 1, and these resinous substances may be discharged from the still through the discharge valve 23.

In Fig. 2, I have shown a duplex still, the members of which may be connected to the chamber 1 in such a way that these members may receive the turpentine alternately.

My present invention provides a distilling apparatus the various elements of which are so constructed and related that the materials or substances may be handled with the greatest facility and efficiency and,

moreover, all of the different steps in the distilling process or treatment may take place simultaneously in the different elements of the apparatus, the operation of the apparatus being practically continuous and, 65 obviously, the greatest capacity is insured with a given size apparatus.

I claim as my invention:—

1. In an apparatus for extracting turpentine and resinous substances from wood, the 70 combination of a pressure-tight retort having means for heating it to distil turpentine from a mass of wood therein, a pressure-tight digester mounted directly below the bottom of the retort and having means for 75 heating it to extract resinous substances from the residue material after the extraction of turpentine therefrom, a pipe forming a fluid-tight connection between the bottom of the retort and the top of the digester, 80 a controlling valve for said pipe, a still connected to receive turpentine from the retort, means for admitting fluid pressure to the retort to forcibly discharge the residue material therefrom through said connecting 85 pipe and into the digester, means for maintaining a circulation of liquid in the digester during the extraction of resinous substances from the mass therein, means for conducting off the resinous substances extracted from the mass in the digester, and 90 means for admitting fluid pressure to the digester to forcibly expel the mass of residue therefrom.

2. The combination of a retort adapted to 95 receive a charge of wood and having means for heating the same to extract turpentine therefrom, a digester arranged to receive the charge of wood from the retort after extraction of the turpentine, the digester 100 having a foraminous support in the bottom thereof for the charge of wood and forming a chamber below it for the collection of the resinous substances, means in the digester for heating the charge of wood therein to 105 extract the resinous substances, means in the digester for causing a circulation of the substances collecting in the chamber in the bottom of the digester to the top of the charge of wood therein, and means for withdrawing the resinous substances from the digester. 110

In testimony whereof I have hereunto set my hand in presence of two subscribing witnesses.
